ATTORNEY

UNITED STATES PATENT OFFICE.

GEORG KARL VILHELM JOHANSON, OF STOCKHOLM, SWEDEN, ASSIGNOR TO AMERICAN GASACCUMULATOR COMPANY, OF ELIZABETH, NEW JERSEY, A CORPORATION OF NEW JERSEY.

ELECTRIC FLASH-LIGHT CONTROLLING MEANS.

Application filed September 25, 1926, Serial No. 137,716, and in Sweden May 1, 1924.

The present invention relates broadly to electric flashlight apparatus but more particularly to means for controlling the flashing of the light.

5 A general object of the invention is to provide a controlling means which is simple in construction but highly efficient in operation.

It also is an object of the invention to provide 10 a device for controlling the flashing of the light or lights of an electric flashlight apparatus comprising novel means for effecting relative movements of the contacts for opening and closing the light circuit.

15 Another object of the invention is to provide a controlling device of the character indicated comprising novel means whereby relative movements of the contacts for opening and closing the light circuit may be effected 20 without any or with a minimum of shock or concussion and consequent or resulting vibrations, the presence of which would cause sparking and consequent rapid deterioration and destruction of the contacts.

25 The foregoing are some of the objects and advantages of the invention but others will be referred to in the detailed description of the invention which follows or will become apparent from such description.

30 In order that the invention may be readily understood and its practical advantages fully appreciated, reference should be had to the accompanying drawing in which I have illustrated certain mechanical structures embodying the invention and disclosing the principle of operation thereof; but it will be understood that the invention is susceptible of embodiment in other mechanical forms than those shown and that various changes in the details of construction 35 may be made within the scope of the claims without departing from the invention or the principle thereof.

In the drawing:

40 Fig. 1 is a view in central vertical section of electric flashlight controlling means embodying the invention;

Fig. 2 is a transverse horizontal section taken on the line 2-2 of Fig. 1;

45 Fig. 3 is a view in side elevation of a fragmentary portion of the structure, the said view being taken from a point looking in the direction of the arrows 3-3 in Fig. 1;

Fig. 4 is a transverse horizontal sectional view taken on the line 4-4 of Fig. 1; 55

Fig. 5 is a view similar to that of Fig. 2 but showing a modified construction of contact actuating means; and

Fig. 6 also is a view similar to that of Fig. 2 but showing still another modified construction of means for actuating and controlling the contacts for controlling the flashlight circuit.

In the drawing 1 designates the base member of the structure having a horizontal bottom or base portion 2 upon which the operative parts of the structure are mounted and supported. Mounted upon the base 1 is a dome-shaped protecting cover 3 for covering and protecting the operative parts of the 70 structure.

Mounted upon the bottom 2 of the base 1 is a block 4 of insulating material upon which is mounted a support 5 in the form of a bracket. The support 5 is provided with an inwardly extended portion 6 from the inner end of which a vertical portion 7 extends which terminates in a horizontally extending portion 8 which constitutes the top of the support. The horizontally extending portion 8 is provided with a tapped opening 9 within which is mounted an adjustable bearing support 10. The lower end of the bearing support is provided with an opening, as shown, within which is mounted a bearing block 11 for the upper end of a vertical shaft 12. The lower end of the shaft 12 is mounted within or upon a bearing block 15 supported upon the bottom 2 of the base centrally thereof. The shaft 12 is insulated from the bearing blocks 11 and 15 by means of sections of insulating material at 16. The adjustable bearing support 10 is adapted to be locked in adjusted position by means of a lock nut 17.

An arm 20 is mounted adjustably upon the lower end portion of the adjustable bearing support 10, having screw threaded connection therewith as shown. One end of the said arm terminates in a point, as indicated at 21, which may cooperate with a calibrated scale (not shown) upon the adjoining end portion of the horizontal extension 8 of the support 5. The opposite end of the arm 20 is provided with a depending lug or projection 22 with which the outer end of a volute

spring 25 is connected, the inner end of the said spring being connected to a sleeve 26 secured by means of a binding screw 27 upon the shaft 12. Normally the spring 25 is in a balanced condition; that is, it does not tend to cause rotation of the shaft 12 in either direction. If altered from that position it tends to return to it, exerting a force corresponding to such tendency upon the shaft 12, 10 tending to rotate it in one direction or the other. A wire friction spring 28 is coiled about the adjustable bearing support 10 and bears at one end against the arm 20 and at its opposite end against the under side of the portion 8 of the bracket support 5. This spring assists in retaining the arm 20 in any position to which it may be adjusted.

A contact carrying lever 30 is also mounted intermediate its ends upon the upper shaft 12. For mounting the said lever upon the said shaft it is provided with upwardly and downwardly extending arms integral with its opposite edges the outer ends of which are bent laterally as indicated at 31. These laterally bent portions are provided with openings within which are mounted and secured headed sleeves 32 which in turn are loosely mounted upon the shaft 12. The upper sleeve 32 may be located as shown in juxtaposition with respect to a sleeve 33 which is adjustably secured in position upon the shaft by means of a binding screw 34. A radially extending arm 35 extends outwardly from the sleeve 33 and the outer end thereof extends downwardly, as indicated at 36, to a point to enable it to contact, during the operation of the device, with one side of the end portion 37 of the lever 30. The purpose of this relationship between the depending portion 36 of the arm 35 and the adjacent end portion or arm of the lever 30 will be hereinafter pointed out.

The opposite end portion 38 of the lever 30 is provided with a contact 39 which is adapted to cooperate with a stationary contact 40 mounted upon a support 41 which in turn is supported upon a block of insulation 42 secured by screws 43 to the upright portion 7 of the bracket support 5. The support 41 is secured to the block 42 of insulating material by means of a screw 45 and a bolt 46 the latter constituting a binding post to which one end of a conducting wire 47 is secured, the opposite end of which may be connected to the positive side of a source (not shown) of electric current.

The end portion 37 of the contact supporting lever 30 is provided with a depending projection 50 to which the outer end of a volute spring 51 is connected by means of a screw 52 or other connecting means. The opposite inner end of the said spring is connected to a sleeve 53 adjustably secured to the shaft 12 by means of a binding screw 54. The upper end of the sleeve 53 consti-

tutes a support or bearing for the lower sleeve 32 previously referred to. The tendency of the spring 51 is to unwind and such tendency operates normally; that is, when the circuit is open, to hold the contact 39 in yielding contact with the stationary contact 40.

Separation of the contact 39 from the contact 40 is effected by contact of the depending portion 36 of the arm 35 which takes place when the shaft 12 is rotated in the direction of the arrows 55 in Fig. 4 and the arrow 56 in Fig. 2. The extent of opening movement of the contact 39 depends upon the extent of rotation of the shaft 12 and the consequent extent of revolution of said depending portion 36.

For the purpose of rotating the shaft 12 in one direction to effect opening movement of the contact 39 I have provided an electro-magnet 60 mounted upon the bottom 2 of the base support and insulated therefrom by means of a sheet of insulation 61. The pole pieces 62 of the electro-magnet extend outwardly and laterally therefrom and terminate at their ends in inwardly extending hook-like portions 63. The magnet armature 64 is mounted upon the shaft 12. The said armature consists, in one form, of a metal plate or bar having spaced parallel splits 65 therein, the portions between and outside of the said splits being bent as indicated at 66 in order to provide a hub or bearing portion through which the shaft 12 extends. The said armature is secured in such position as may be desired by means of a binding screw 67.

When the device is not in operation and the circuit through the coil of the electro-magnet 60 is open the armature 64 occupies some such position as that indicated in Fig. 4 with respect to the inwardly extending end portions 63 of the pole pieces 62. The light by means of which the flashing signals are effected is included in the same circuit as that of the electro-magnet 60 and may be either in series or parallel with the winding thereof, as may be preferred.

The complete circuit, the light, and the switch by means of which the circuit may be permanently broken and the operation of the device discontinued when it is desired to discontinue the same, are not shown because they may be of any known type and construction.

Mounted upon the shaft 12 is a bar or plate 70 of metal or other suitable material which, by its inertia, when the device is in operation cooperates with the electro-magnet and its armature previously referred to in controlling the movements of the lever 30 upon which the movable contact 39 is mounted. The bar 70 is directly mounted upon a sleeve 71 which in turn is mounted upon the shaft 12. The said bar operates in a manner

similar to that of a pendulum and therefore may be referred to as a pendulum bar, and the said bar together with the shaft 12 may be regarded as a pendulum device.

If it now be assumed that current is flowing to the device through the conductor 47 it will flow through the member 41, thence through the contacts 40 and 39, the lever 30 to the shaft 12, through the spring 25, the arm 20, the support 5, thence through a conductor 72 to the winding of the electro-magnet and the light back to the current source. As before stated, the winding of the electro-magnet and the light may be in series or parallel, as preferred. Such flow of current will energize the electro-magnet and cause quick or rapid movement of the armature 64 from some such position as that shown in Fig. 4 into alinement with the inwardly extended portions 63 of the pole pieces 62. Such movement causes rotation of the shaft 12 and the parts or elements rigidly secured thereto in the direction of the arrows 55. The angular or rotary movement of the shaft 12 thus effected causes movement of the arm 35 to carry the depending portion 36 thereof into contact with the adjoining portion 37 of the lever 30 which carries the contact 39 and causes movement of the said lever to open the said contact. The circuit is thereby broken but the movement of rotation of the shaft 12 and the parts carried thereby continues under the influence of inertia, particularly the inertia of the bar 70. Such movement places the spring 25 under tension which tends to stop the said movement and to cause movement in the opposite direction. Finally the effects of friction and of the spring 25 are sufficient to stop the movement of rotation started by the movement of the armature 64 whereupon the spring 25, which has been placed under tension, causes movement of the parts in the opposite direction. Such movement in the opposite direction causes the depending portion 36 of the arm 35 to release or to move away from the portion 37 of the lever 30 and to permit the spring 51 to cause movement of the lever 30 about the shaft 12 to carry the contact 39 again into engagement with the stationary contact 40, whereupon the circuit is again closed. The inertia of the moving parts, including the relatively heavy bar 70, causes continued reverse movement of rotation of the said parts, causing further separation of the opposite ends of the armature 64 from the inwardly extending portions 63 of the pole pieces 62 in opposition to the springs 25 and 51 and to the force of attraction between the said armature and the said portions 63. The forces due to the said springs and to the attraction between the armature and the pole pieces finally causes stoppage of the reverse movement of the said parts, whereupon the armature is attracted to a position in alinement with the inwardly extended portions 63 of the pole pieces and thus again causes movement of the shaft 12 and of the arm 35 with its projection 36 in a direction to effect pivotal movement of the contact carrying lever 37 to move the contact 39 into open position or away from the contact 40. This operation is repeated over and over again during the time that the control device is in use.

A stop 75 may be adjustably mounted upon the bar 70 and if desired may be moved into position as indicated in dotted lines to contact with the inwardly extending portion 6 of the supporting bracket 5 to limit the movement of the said bar and of the shaft 12 in one direction.

In Fig. 5 I have shown a modified construction of means for supporting the movable contact of the cooperating contacts 39 and 40 previously referred to. In the construction as illustrated in this figure the parts 5, 12, 39, 40, 41, 42, 45, 46, 47, 51, 52, 35 and 36 are identical with the parts correspondingly numbered in Figs. 1 to 4 of the drawing.

The outer end portion of the spring 51 in said Fig. 5 is connected to one end portion 37' of a lever 30' mounted upon the shaft 12 in identically the same manner as the contact lever 30 is mounted upon the said shaft. The opposite end portion 38' of the lever 30' contacts with a plate 76 which together with the contact 39 is secured to a longitudinally movable supporting rod 77. The said rod 100 is slidably mounted within an opening through a bracket or support 78 mounted in any convenient manner upon the bottom 2 of the base 1. A wire spring 79, coiled about the rod 77 and bearing at one end against the support 78 and at its opposite end against the plate 76, operates to hold the contact 39 in engagement with the contact 40. The said contact is adapted to be separated from the contact 40 by rotation of the lever 30' about the shaft 12 in the direction of the arrow 80. Rotation of the said lever 30' is effected in the direction of the arrow 80 and in the opposite direction in exactly the same manner as rotation of the contact bearing lever 30 is effected.

In the construction as shown in Fig. 6 the parts 5, 12 and 42 are identical with the parts correspondingly numbered in the preceding figures of the drawing. The stationary contact 40' is mounted upon the insulating member 42 by means of a bolt 81 which also constitutes a binding post to which one end of the conductor 47 is connected. The contact 40' as shown may constitute the head of the bolt 81. The contact 39' is mounted upon the outer end of the arm 82 of an angular lever the other arm 83 of which extends inwardly and terminates in cooperative relation to the cam surface of a cam 130

member 84 mounted upon the shaft 12. The said arm 83 is provided with a roller 85 which bears against the cam surface of the said cam. The lever is provided with a projection or ear 86 which is pivoted by means of a pivot 87 upon an ear 88 which projects outwardly from the bar or plate 90 secured by means of a screw 91 to the insulating block 42. A wire spring 92 is coiled about 10 the pivot 87 and one of its ends is hooked around an edge of the ear or projection 88. The said spring bears against a portion of the arm 82 of the angular lever. The tendency of the spring 92 is to unwind and its 15 tendency also is to hold the contact 39' in engagement with the contact 40'. Rotation of the shaft 12 and the parts carried thereby including the cam 84 is effected in identically the same manner as described in connection 20 with Figs. 1 to 4 inclusive, and the operation and the function of the structure embodying the means as shown in Fig. 6 are identical with the operation and function of the construction as disclosed in and described 25 in connection with Figs. 1 to 4 inclusive.

In the several forms of construction shown the movement of the movable contact into engagement with the stationary contact is effected by the combined action of the spring 30 25 and the springs 51, 79 and 92 which are associated with the respective movable contacts. In the operation of the device the movable contact is seated gently or softly 35 upon the stationary contact and does not strike the same with a hard blow so as to produce vibrations such as would cause the production of sparks between the adjoining faces of the contacts. The consequence of 40 this is that the surfaces of the contacts are not worn away as would be the case if the contacts came together with a blow followed by immediately succeeding vibrations.

Any suitable means other than that shown 45 may be employed for effecting opening and closing movements of the movable contact to effect flashing of the light, provided, however, that the movable contact is actuated by a spring or other suitable yielding means the 50 tendency of which is to hold the contacts pressed together or in yielding contact with each other.

Having thus described my invention, what I claim and desire to secure by Letters Patent is:

1. In electric flashlight controlling means, the combination of relatively movable contacts, yielding means tending to hold said contacts in closed relation to each other, means movable in one direction for causing relative movements of said contacts to open the same, and other yielding means adapted to act upon said second named means to cause movement thereof in the opposite direction to permit relative movements of said

contacts into closed relation with respect to each other.

2. In electric flashlight controlling means, the combination of a stationary and a movable contact, yielding means tending to hold the movable contact in engagement with the stationary contact, movable means operating upon the closing of said contacts to cause movement of the movable contact into open position, and other means thereafter acting 70 upon the second named means to cause movement thereof in a direction to permit the said yielding means to cause closing movement of the said movable contact.

3. In electric flashlight controlling means, 80 the combination of a movable and a stationary contact, electrically actuated means for effecting opening movement of the said movable contact, yielding means tending to hold the said movable contact in closed position, 85 and yielding means for causing movement in the opposite direction of the electrically actuated means to permit closing movement of the said movable contact.

4. In electric flashlight controlling means, 90 the combination of relatively movable contacts, electrically actuated means for effecting relative movements of said contacts to open the same, yielding means mounted upon the said electrically actuated means which 95 tends to hold the said contacts in closed relation to each other, and other yielding means adapted to cause movement of the said electrically actuated means in the opposite direction to permit relative closing movements of the said contacts.

5. In electric flashlight controlling means, the combination of a pendulum device, electric contacts one of which is rotatably mounted on the said pendulum device, yielding 105 means tending to hold the said electric contacts in engagement with each other, means for causing movement of the said pendulum device in one direction to effect relative opening movements of the said contacts, and yielding means for effecting movement of the said pendulum device in the opposite direction to permit relative closing movements of the said contacts.

6. In electric flashlight controlling means, 115 the combination of an oscillatable shaft, electric contacts, one of which is loosely mounted upon the said shaft and adapted to rotate with respect thereto, means for effecting rotative movement of the said shaft 120 in one direction, means adapted to engage the support of the contact carried by said shaft to effect movement of the said contact out of engagement with the stationary contact, and yielding means having connection 125 with the said shaft and operating to cause rotative movement thereof in the opposite direction to permit closing movement of the contact mounted upon the said shaft.

7. In electric flashlight controlling means, 130

the combination of an oscillatable shaft, a stationary contact, a movable contact, means loosely mounted upon the said shaft for supporting said movable contact, yielding means having connection at one end to said shaft and at its opposite end to said movable contact supporting means and tending to cause closing movement of the said movable contact means for effecting rotation of the said shaft in one direction, means carried by said shaft for engaging the movable contact support to cause opening movement of the said movable contact, and yielding means having connection with the said shaft and operating to effect rotative movement thereof in the opposite direction to permit closing movement of the said movable contact. 70

posite sides of the said shaft, which poles are provided with inwardly extending projections, an armature mounted upon the said shaft and extending in a plane normally out 5 of alinement with the plane of the inwardly extending portions of the said poles, the said armature being adapted to move into alinement with the said inwardly extending portions of the said poles upon energization of 10 the said electro-magnet to cause rotation of the said shaft in one direction, a movable contact, a lever rotatably mounted upon the said shaft upon one end of which the said movable contact is supported, yielding means

interposed between the said lever and the 15 said shaft which tends to hold the movable contact pressed against the stationary contact, means carried by said shaft for engaging the said lever when the said shaft is rotated by the actuation of the said armature, and yielding means operating to cause movement of the said shaft in the opposite direction to permit closing movement of the movable contact, substantially as described.

In testimony that I claim the foregoing as 20 my invention, I have hereunto signed my name this 10th day of September, 1926.

GEORG KARL VILHELM JOHANSON.
